UNITED STATES PATENT OFFICE

ERNEST H. HOLZWOERTH, OF BUFFALO, NEW YORK

BLAST-FURNACE TUYÈRE

Application filed July 11, 1929. Serial No. 377,434.

This invention relates to improvements in blast furnace tuyères.

Its object is the provision of a tuyère of this character which has been designed to reduce burning thereof to a minimum by continuously agitating the materials in the furnace adjacent the tuyère and thereby preventing pools of molten metal forming adjacent to the tuyère and burning it.

10 In the accompanying drawings:—

Figure 1 is a longitudinal section of a tuyère embodying my invention. Figure 2 is a transverse section thereof on line 2—2, Figure 1. Figure 3 is a horizontal section of 15 the tuyère taken on line 3—3, Figure 2. Figure 4 is a fragmentary sectional view of a slightly modified form of the invention.

Similar characters of reference indicate corresponding parts throughout the several 20 views.

The numeral 10 indicates a part of the furnace wall in which the improved tuyère is mounted in the usual and well known manner. As is customary, the tuyère consists of 25 a substantially frusto-conical body 11 made of a copper alloy or other appropriate material and having the usual passage 12 for the admission of a continuous blast of air to the furnace, this passage being connected 30 at its outer end with the source of air supply by a pipe 13. The tuyère body has a cooling compartment 14 surrounding its air passage and through which a fluid is circulated by means of an inlet pipe 15 and an outlet 35 pipe 16.

For the purpose of destroying the state of rest condition of the molten materials which usually collect around the underside of the nose of the tuyère and which cause its burning, I provide a notch or slot 17 in the bottom side of the nose end of the tuyère for the purpose of introducing a portion of the air blast flowing through the passage 12 into the materials beneath and immediately in front 40 of the tuyère. This notch is preferably dis-

posed radially and extends outwardly a suitable distance from the nose-edge, the same being longer than it is wide, with its bottom at right angles to the tuyère-axis. In the modified form of slot indicated at 18 in Figure 4, its bottom wall is downwardly and forwardly inclined. While I have shown one slot for introducing a downward blast of air through the lower wall of the nose, it is to be understood, that, if desired, two or more 50 slots may be employed.

The provision of the slot 17 in the bottom edge of the tuyère-nose permits of a continuous downward blast of air directly in the materials which disburses the eddy currents 55 usually formed at the nose end of the tuyère due to the whirling motion of the main air blast introduced through the tuyère passage 12. Furthermore, the main air blast tends to create a slight vacuum about the nose end of the tuyère which acts to set up eddy currents, 60 these currents in turn melting out pockets adjacent to the tuyère in which molten metal is trapped, causing the tuyère-nose to burn. The presence of one or more slots in the 65 tuyère, disposed as shown, acts to destroy this condition and keeps the material agitated and in constant motion with the result that the portion of the tuyère, which is subject to burning, is practically insulated from 70 the molten materials and is thereby kept from burning. The slot, extending to the nose edge of the tuyère, effectually permits the air blast introduced through it to be also 75 directed forwardly to prevent the molten materials adhering to the lower front edge of the tuyère-nose.

I claim as my invention:—

1. A blast furnace tuyère, comprising a body having a passage for the admission of air to the furnace above the level of the molten materials therein and an auxiliary passage comprising a forwardly-opening notch formed in the bottom side of the nose end of the tuyère-body and at the edge there- 80 85 90 95

of for delivering air under pressure downwardly from the first-named passage into the materials of the furnace to keep them in constant motion about the nose end of the tuyère.

5 2. A blast furnace tuyère, comprising a body having a substantially radial notch extending through its wall, said notch being disposed in the bottom side of the nose end 10 of the tuyère and at the edge thereof.

ERNEST H. HOLZWORTH.
